ALEX TAUB, OF DETROIT, MICHIGAN

CONDENSER AND PROCESS OF MAKING THE SAME

Application filed May 3, 1926. Serial No. 106,315.

The present invention relates to condensers and processes of making the same.

Among the objects of the invention is to facilitate and cheapen the manufacture of 5 double wall tubing which is recognized as being highly efficient for condensers, water being led through the inner tube and the fluid to be condensed or cooled being led through the outer tube between the two 10 walls.

Another object is to provide a tube of the kind indicated which will more accurately retain its spacing between the walls when bent or curved to suitable shape.

15 Still another object is a cheap and efficient process of making such tubing and condensers.

Other objects will readily appear to those skilled in the art upon reference to the following description and drawings in which:

Fig. 1 is a conventional representation of a condenser of the type indicated.

Fig. 2 is a cross section of the present form of tube.

25 Figs. 3, 4, and 5 are sectional views indicating several steps in the formation of the tube.

As indicated in the drawings, the tubing is to be made from flat stock, a strip for example, of copper, of suitable width being 30 passed through a series of rolls adapted to form the tube in several stages.

The rolls are preferably so shaped and arranged that the first stage forms the strip 35 10 into the form indicated in Fig. 3, that is, with a suitable channel 11 along one edge. The next rolls will then form the channeled portion into a tube like part 11^a with the flat portion 10^a bent back on itself as at 12. This 40 stage is indicated in Fig. 4.

The third stage forms the portion 10^a to the form shown at 10^b in Fig. 5, that is, as the outer tube.

The tubing from the third stage is then 45 passed through a welding or soldering step to join both free edges 13 and 14 to the double edge 12 as shown in Fig. 2 at 15, whereupon the tubing so formed is wound around a suitable form to produce the condenser 50 coil 20 such as indicated in Fig. 1.

After the coil is so formed the ends of the outer tube are preferably trimmed off and closed around the extending inner tube and side connections made with the outer tube as indicated at 21.

As in similar condensers, water is passed through the inner tube 11^a and the fluid to be cooled or condensed passed through the connections 21 and the outer tube.

The tubing formed in the above outlined process consists of an inner tube having a surrounding outer tube tangent thereto with the tubes secured together along the line of contact by means of the weld. It should be noted that the term "welding" is 65 to be understood to include also brazing and soldering.

In winding the tubing upon the form to produce the condenser coil it is preferred to lead it upon the form in such position that the seam 15 lies substantially in the plane of the curve. This arrangement prevents displacement of the inner coil and thereby maintains proper spacing between the inner and outer walls,—a feature which is difficult 70 if not impossible when coiling two distinct tubes.

Having now described the invention and the preferred forms of embodiment thereof, it is to be understood that the said invention 75 is not to be limited to the specific details herein described and illustrated but only by the scope of the claims which follow.

I claim:

1. A double walled tube formed of a single strip of sheet metal bent upon itself along a line parallel to its edges to constitute inner and outer tubes, the edges of said strip being united at and to the strip at the line where it is bent upon itself.

2. As an article of manufacture, double walled sheet metal tubing having its inner wall continuous with the outer wall and having a single seam serving to seal both tubes, said tubing being made of flexible metal whereby said tubing may be bent to a suitable form.

ALEX TAUB.
